SASH BALANCE CONNECTOR

Alvin R. Larson, Stamford, Conn., assignor to S. H. Pomeroy Company, Stamford, Conn., a corporation of New York

Filed Feb. 12, 1960, Ser. No. 8,376
3 Claims. (Cl. 16—197)

This invention relates to spiral sash balances and, more particularly, to means for adjusting the spring tension of a spiral sash balance.

Spiral sash balances in general are described in U.S. Patent No. 1,864,745, and U.S. Patent No. 2,792,588 describes a means for adjusting the tension produced by the springs in sash balances. While the foot mechanism for adjusting the spring tension described in the latter patent has proved to be satisfactory in most circumstances, there has been a need for an adjustable foot mechanism that, while providing similar advantages, is simpler and sturdier in construction and more economical to manufacture.

Accordingly, it is a purpose of this invention to provide a foot mechanism for a spiral sash balance that permits the spring tension of a balance to be adjusted after the balance has been installed and is very economical to manufacture and sturdily constructed. This purpose is attained by providing an adjustable foot mechanism that includes a channel member that is adapted to be fixedly attached to a window sash, a coupling member that is adapted to be fixedly attached to the spirally wound strip of a sash balance, the channel member having recesses formed therein adapted to releasably engage the coupling member, and the coupling member being adapted to cooperate with a tool for disengaging the coupling member from the channel member.

This invention may be more completely understood from the following detailed description of representative embodiments of the invention taken in conjunction with the accompanying figures of the drawing in which—

FIGURE 1 is a view of an adjustable foot mechanism constructed in accordance with the invention;

FIGURE 2 is an illustration of an adjustable foot mechanism connected to a window sash;

FIGURE 3 is a view taken along the line 3—3 of FIGURE 2;

FIGURE 4 is a view taken along the line of 4—4 of FIGURE 2;

FIGURE 5 is a top view of an adjustable foot mechanism; and

FIGURE 6 is a perspective view of a channel member for an adjustable foot mechanism.

With reference to FIGURES 1 and 2, there is illustrated a U-shaped channel member 11 that has an elongated recess 12 formed in each side and a hook 13 formed at the mouth of each recess. A foot plate 14 fashioned on the bight portion of the channel member 11 has an upturned tooth 15 formed at its ends. A plurality of holes 16 are provided in the foot plate 14 and in the bight portion of the channel so that nails 17 can be driven through them and into a wooden sash 18 as illustrated in FIGURE 2.

As is best shown in FIGURES 1 and 2, a sash balance having a foot mechanism constructed in accordance with the invention is mounted on a window by first attaching the upper end of a member that includes a spiral spring 19, a spirally wound strip 20, and a nut 21 to a window frame as explained in the aforementioned Patent No. 2,792,588. The channel member 11 is attached to the lower end of the window sash as previously explained and the strip 20 is releasably coupled to the channel member 11 by a spring coupling 22, shown in greater detail in FIGURES 3 and 4.

2

The spring coupling 22 is U-shaped and is adapted to be received within the recesses 12 in the channel member 11, and a hole 23 is formed in each side of the coupling which is adapted to receive a hollow rivet 24. Each side of the coupling 22 has an outwardly extending spring portion 25 formed thereon by cutting slots 26 into it and bending the portion 25 outwardly. As is best shown in FIGURES 2 and 4, the coupling 22 is attached to the member 11 by forcing the coupling 22 upwardly into the recesses 12 in the member until the lower end of the straight sides of the coupling catches on the inwardly extending hooks 13. The force of the spring portions 25 of the coupling against the walls of the recesses maintains the coupling in position.

To disengage the coupling 22 from the member 11 for the purpose of adjusting the pull produced by the sash balance, a tool 27 that is turned over on one end 28 is inserted into the hole in the rivet 24 and twisted in the direction indicated by the arrow in FIGURE 1. With the channel member 11 being held stationary, the spring portions 25 are forced against the walls of the recesses 12 and bend inwardly until the flat sides of the coupling 22 disengage from the hooks 13. Then the coupling 22 can be withdrawn from the recesses 12 and the tension produced by the sash balance adjusted prior to reinserting the coupling back into the recesses 12.

An alternative method of fastening a channel member 11 to a window sash is illustrated in FIGURE 5 and may be desirable where the sash is made of metal. The member 11 is formed with at least one hole 29 in its bight portion through which metal screws 30 are inserted and threaded into a metal window sash 31. The window sash is illustrated in FIGURE 5 in combination with a window pane 32 and a sealing material 33. The channel member 11 does not have a foot plate 14 and tooth 15 but is otherwise exactly the same as the type shown in FIGURES 1—4. Two holes 34 formed in the sides of the member 11 are provided for convenience so that the member can also be attached to a window sash by inserting screws or nails through these holes.

FIGURE 6 illustrates both embodiments of the channel member 11 with the foot plate 14 and tooth 15 being shown in phantom.

It is apparent that a novel and useful adjustable foot mechanism for a spiral sash balance has been provided. This type of foot mechanism provides a simple, sturdy and economical method of releasably attaching the spirally formed strip to the channel member 11 in such a manner that it can be easily connected to and disengaged from the receptacle member 11.

While representative embodiments of the present invention have been shown and described for purposes of illustration, it is apparent that the embodiments are susceptible of change and modification without departing from the scope of the invention in its broader aspects. Therefore, the invention described herein is not to be construed as limited to the specific embodiments described, but is intended to encompass all modifications thereof coming within the scope of the following claims.

60 I claim:

1. An adjustable foot mechanism for a spiral sash balance extending along the side of a window sash comprising a first member adapted to be affixed to a window sash and having a portion extending generally parallel to the side of the sash, said portion having an open-ended slot therein, said slot having a hook at the open end thereof projecting generally perpendicularly to the extent of the slot, and a second member attached to the spirally wound strip of a sash balance, said second member being adapted to be received in said slot formed in said first member through the open end thereof by motion parallel to the

side of the window sash, said second member having a spring portion formed thereon which is adapted to force said second member into engagement with the sides of said slot inside said hook so as to lock said second member longitudinally into said slot of said first member.

2. An adjustable foot mechanism for a spiral sash balance extending along the side of a window sash comprising a first member adapted to be affixed to a window sash and having a portion extending generally parallel to the side of the sash, said portion being generally U-shaped, each leg of said portion having an open-ended slot therein, each slot having a hook at the open end thereof projecting generally perpendicularly to the extent of the slot, and a second member adapted to be attached to the spirally wound strip of a sash balance, said second member being adapted to be received in said slots formed in said first member through the open ends thereof by motion parallel to the side of the window sash, said second member having a spring portion formed thereon which is adapted to force said second member into engagement with the sides of said slots inside said hooks so as to lock said second member longitudinally into said slots of said first member.

3. A spiral sash balance comprising a spirally wound strip adapted to extend along the side of a window sash, means in cooperative engagement with said strip in which torsional force may be stored, a first member adapted to

4
be affixed to a window sash and having a portion extending generally parallel to the side of a sash, said portion having two spaced open-ended slots therein, said slots having oppositely directed hooks at the open ends thereof each projecting generally perpendicularly to the extent of the corresponding slot in a direction opposite to the torsional forces normally exerted by said first-mentioned means, a second member attached to the spirally wound strip, the second member being adapted to be received in said slots through the open ends thereof by motion parallel to the extent of the slots and having spaced apart spring means formed thereon forcing the second member into engagement with the sides of the slots inside the hooks when the second member is so received so as to lock said second member longitudinally into said slots, said spring means being arranged to urge said second member in the same rotational direction as the direction in which said spirally wound strip is normally urged.
